UNITED STATES PATENT OFFICE.

WALTER D'ARCY RYAN, OF SCHENECTADY, NEW YORK.

DESIGN FOR A LENS FOR VEHICLE LAMPS.

Application filed December 27, 1926. Serial No. 20,161. Term of patent 14 years.

To all whom it may concern:

Be it known that I, WALTER D'ARCY RYAN, a citizen of the United States, and a resident of the city of Schenectady, county of Schenectady, and State of New York, have invented a new, original, and ornamental Design for a Lens for Vehicle Lamps, of which the following is a specification, references being had to the accompanying drawings, forming a part thereof.

In the drawings,

Figure 1 is a front elevation of the lens.

Fig. 2 is a side elevation thereof.

I claim:

The ornamental design for a lens for vehicle lamps, as shown.

WALTER D'ARCY RYAN.
